FIG1

FIG2

FIG3

FIG4

FIG5

FIG6

FIG. 1 is a perspective view of the flashlight showing my new design as taken from the top and left side;

FIG. 2 is a perspective view showing the bottom and left side of the design;

FIG. 3 is a top plan view of the design;

FIG. 4 is a bottom plan view of the design;

FIG. 5 is a rear elevational view of the design;

FIG. 6 is a front elevational view of the design.

The right side of the design has the same appearance as the left side illustrated in FIG. 1.

I claim:

The ornamental design for a flashlight, as shown and described.
